RAILWAY SIGNALING APPARATUS

Francis J. Ryan, Chicago, Ill., assignor to The
Union Switch & Signal Company, Swissvale,
Pa., a corporation of Pennsylvania

Application December 15, 1937, Serial No. 179,970

3 Claims. (Cl. 246—33)

My invention relates to railway signaling apparatus, and particularly to control circuits for signals capable of displaying a plurality of indications for directing traffic movements along a stretch of railway track.

One feature of my invention is the provision of novel and improved means for protecting against crosses between the line wires of circuits for controlling a plurality of indications displayed by each signal.

I shall describe one form of apparatus embodying my invention, and shall then point out the novel features thereof in claims.

The accompanying drawing is a diagrammatic view showing one form of apparatus embodying my invention.

Referring to the drawing, the reference characters *a* and *b* designate the rails of a stretch of railway track along which traffic may normally move in either direction. These rails are divided by insulated joints 5 to form a plurality of track sections 1T, A1T and A2T. Under some conditions, however, these three sections could be combined into one section, or could be divided into some other number of sections.

Each track section is provided with a track circuit including a source of current, shown as a battery 6, connected across the rails adjacent one end of the section, and a track relay, designated by the reference character R with a distinguishing prefix corresponding to the reference character for the associated track section, connected across the rails adjacent the other end of the section.

At one end of the stretch, a signal designated by the reference character 1 is shown for governing traffic movements in a given direction into the stretch, and a signal designated by the reference character 4 is shown for governing traffic movements in the opposite direction out of the stretch. At the opposite end of the stretch, a signal designated by the reference character 3 is shown for governing traffic movements in the given direction out of the stretch, and a signal designated by the reference character 2 is shown for governing traffic movements in the opposite direction into the stretch. As here shown, these signals are of the semaphore type, but they may be of any other suitable form.

A contact designated by the reference character 25 is shown as being operated in conjunction with signal 3, and is arranged to be closed when signal 3 is displaying a proceed or caution indication for directing traffic movements out of the stretch, but to be open when signal 3 indicates stop. A similar contact designated by the reference character 16

is shown similarly operated in conjunction with signal 4.

A control relay is provided for each signal, designated by the reference character HR with a distinguishing numerical prefix corresponding to the reference character of the associated signal. A second control relay is shown for each of the signals 1 and 2, designated by the reference character DR with a distinguishing numerical prefix corresponding to the reference character of the associated signal. Each HR relay controls a first indication of the associated signal, which may be the home or caution indication, and each DR relay controls a second indication of the associated signal, which may be the distant or proceed indication.

An asymmetric unit which may be of the well-known copper oxide rectifier valve type, designated by the reference character 23, is included in the control circuit for relay 1DR. This unit has the characteristic that it permits current to flow through it freely in the direction indicated by the arrowhead portion of its symbol, that is, it has low resistance to current flowing in that direction, but obstructs the flow of current in the opposite direction, that is, it has high resistance to the flow of current in the opposite direction. A similar asymmetric unit, designated by the reference character 15, is included in the control circuit for relay 2DR.

As shown in the drawing, relay 1HR is normally energized by a circuit passing from a given terminal of a source of current, here shown as a battery 17, through front contact 18 of relay 3HR, contact 19 of relay A2TR, conductor 20, contacts 21 and 22 of relays A1TR and 1TR, respectively, winding of relay 1HR, conductor 14, and return conductor 13 back to the opposite terminal of battery 17. With relay 1HR energized, a circuit, not shown, is closed for operating the arm of signal 1 to the caution position, this circuit being similar to the circuit shown for signal 2 passing from a battery 26, through contact 27 of relay 2HR, mechanism of signal 2, and contact 29 of relay 2HR back to battery 26.

Relay 1DR is energized by a circuit which includes the portion of the circuit traced for relay 1HR passing from battery 17 through the contacts of relay 3HR and the track relays, and thence passing through asymmetric unit 23 in the low resistance direction, winding of relay 1DR, a second return conductor 24, and contact 25 of signal 3, back to battery 17. With relay 1DR energized, a circuit, not shown, is closed for operating the arm of signal 1 to the proceed position,

this circuit being similar to the circuit shown for signal 2 passing from battery 26, through contact 27 of relay 2HR, contact 28 of relay 2DR, mechanism of signal 2, and contact 29 of relay 2HR, back to battery 26.

Relays 2HR and 2DR for signal 2 are energized by circuits similar to those already traced for relays 1HR and 1DR, respectively, and can, therefore, be readily traced on the drawing without further description.

I shall now assume that, with the circuits for relays 1HR and 1DR arranged as already described, the circuit for relay 1HR is closed from battery 17 through conductor 20, but is open between conductor 20 and the winding of relay 1HR, on account of contact 21 of relay A1TR or contact 22 of relay 1TR being open, or on account of a broken conductor. I shall also assume that the circuit for relay 1DR is open at contact 25 of signal 3. If, under these conditions, there should be a cross between conductors 20 and 24, asymmetric unit 23 would prevent false energization of relays 1HR and 1DR by current flowing from battery 17 by way of the cross between conductors 20 and 24.

I shall next assume that the circuit for relay 1HR is closed between contact 19 of relay A2TR and the winding of relay 1HR, but that contact 19 is open. I shall also assume that the circuit for relay 1DR is closed. If, under these conditions, there should be a cross between conductors 20 and 24, the two terminals of relay 1HR would be connected to the same terminal of battery 17, and hence relay 1HR would not be falsely energized.

It follows that the arrangement shown for circuits for controlling two different indications of a signal, and an asymmetric unit placed as shown, provide effective cross protection for such circuits.

By the accompanying drawing, my invention is shown applied to circuits for signals for governing traffic movements in both directions along a single track, but it could also be similarly applied to circuits for signals for tracks over which traffic movements normally are in one direction only, such for example as the tracks of a double track line, one track of which is used for traffic movements in a given direction and the other track of which is used for traffic movements in the opposite direction.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track including one or more track sections, a track circuit for each of said sections each including a track relay, a signal capable of indicating proceed or caution or stop for governing traffic movements into said stretch in a given direction, a second signal capable of indicating stop or of displaying an indication directing traffic movements out of said stretch in said given direction, a contact operated by said second signal and open when said second signal indicates stop but closed when said second signal is displaying an indication for directing traffic movements out of said stretch, a proceed control relay and a caution control relay for said first signal, an asymmetric unit permitting flow of current in a given direc-

tion but obstructing flow of current in the opposite direction, a circuit portion passing from a source of current through a front contact of each of said track relays, a circuit for energizing said caution control relay including said circuit portion and thence passing through the winding of said caution control relay and by a return conductor to the opposite terminal of said source of current, a second circuit for energizing said proceed control relay including said circuit portion and thence passing through the winding of said proceed control relay in series with said asymmetric unit in said given direction and thence by a second return conductor through the contact operated by said second signal to the opposite terminal of said source of current, and means controlled by said caution and proceed control relays when energized for causing said first signal to indicate caution or proceed respectively.

2. In combination, a stretch of railway track, a signal capable of indicating proceed or caution or stop for governing traffic movements into said stretch, a first contact controlled by traffic conditions in said stretch closed when said stretch is unoccupied but open when said stretch is occupied, a second contact controlled by traffic conditions a given distance in advance of said stretch closed when the track is unoccupied within said given distance but open when the track is occupied within said given distance, a proceed control relay and a caution control relay for said signal, an asymmetric unit permitting flow of current in a given direction but obstructing flow of current in the opposite direction, a circuit portion passing from a source of current through said first contact, a circuit for energizing said caution control relay including said circuit portion and thence passing through the winding of said caution control relay and back to the opposite terminal of said source of current, a second circuit for energizing said proceed control relay including said circuit portion and thence passing through the winding of said proceed control relay in series with said asymmetric unit in said given direction and through said second contact back to said opposite terminal of the source of current, and means controlled by said caution and proceed control relays when energized for causing said first signal to indicate caution or proceed respectively.

3. In combination, a stretch of railway track, a signal capable of displaying a first or a second indication for directing traffic movements into said stretch, a first and a second contact, means for separately closing said contacts, a first control relay and a second control relay for said signal, an asymmetric unit permitting flow of current in a given direction but obstructing flow of current in the opposite direction, a circuit portion passing from a source of current through said first contact, a circuit for energizing said first control relay including said circuit portion and passing through the winding of said first control relay back to the opposite terminal of said source of current, a second circuit for energizing said second control relay including said circuit portion and thence passing in said given direction through said asymmetric unit and through the winding of said second control relay and also through said second contact back to said opposite terminal of the source of current, and means controlled by said first and second control relays when energized for causing said signal to display said first and second indications respectively.
